UNITED STATES PATENT OFFICE.

ALFRED LECLERC, OF PARIS, FRANCE.

CYLINDER SAFETY-LOCK.

1,188,285.

Specification of Letters Patent. Patented June 20, 1916.

Application filed August 13, 1914. Serial No. 856,697.

To all whom it may concern:

Be it known that I, ALFRED LECLERC, a citizen of the French Republic, and resident of Paris, France, have invented certain new and useful Improvements in Cylinder Safety-Locks, of which the following is a specification.

This invention relates to a safety lock the mechanism of which takes up only a minimum of room while having the maximum of strength.

The object of this invention is to provide a safety lock the mechanism of which is in the shape of a cylinder not thicker than the pipe of the ordinary safety locks, the advantage being that nearly all the parts of the mechanism can be shaped on the lathe and therefore, at a very low cost-price.

Another object of the invention is to provide a safety lock which from the inside of the door is actuated by means of a knob and from the outside by means of a key. The lock may be combined or not with an alarm bell.

The accompanying drawing, given by way of example, shows one form of embodiment of the invention and in this drawing:

Figure 1 is a longitudinal section of lock; Fig. 2 is a cross section of same. Fig. 3 is a disassembled perspective view of the lock.

The safety lock comprises a cylindrical body 1 one of the ends of which is provided with an inner border or flange 2. The outside of this body is screw-threaded at 3 so as to be able to receive a tightening nut 4 upon which the two small posts 5 are mounted which are intended to support a wheel carrying rings 6 which by striking against the bell 7 serve to cause the bell to ring.

The wheel carrying the rings 6 is driven by a small pinion 8 which is rigidly secured to the shaft 9 and meshes with the toothed wheel 10 which in turn is rigidly connected with the actuating knob of the lock bolt and with a cylindrical member 11 termed piston. The latter carries at one of its ends four pins 12 which are united at their opposite end by

means of a disk 13 thus forming a small pinion or lantern intended to mesh with the bolt 14 in which a toothed rack 15 has 50 been cut.

The gear lantern carries in its center two sliding bars 16, the ends 17 of which are bent at right angles and are engaged in a groove provided in the disk 13, the other 55 ends being inserted in a hole 18 provided in the piston 11 which serves as a housing for a spring 19 which pushes the bars 16 into locking position.

The piston which carries the lantern pinion is provided at one end with a disk 23, and between this disk and the main body portion of the piston, there is further provided a reduced portion which forms in effect an annular groove, designated 20. A notch 21 is 60 formed in the edge of the disk 23, the said notch being for the purpose of engaging a stop screw 22, which is held in the casing 1, thereby preventing rotation of the piston and lantern pinion. A spring 24 is inclosed 65 within the casing 1, and bears with its ends against the interior of the casing and the disk 23.

The disk 13 is provided with an opening 70 corresponding to the bit 26 of the key 75 which bit can only engage in the said opening after the end 27 of the key has shifted the bars 16, the part 28 of the bit remaining outside the disk 13.

This safety lock works as follows: The 80 key having been inserted into the key-hole 29 of the lock, the end 27 of the key pushes the bars 16 back which take up the positions 30 shown by dotted lines in Fig. 3. The part 26 of the bit of the key then engages in 85 the hole 25 and extends through the thickness of the disk 13. Upon applying an additional pressure to the key the tumbler carrying the lantern pinion will be pushed back against the tension of the spring 24 until the 90 pin 22 becomes seated in the annular groove 20. It will be noted that the end of the key is partly cut away, as indicated at 27; this results in sliding one-half of the bar 16 a

greater distance than the other half, thus throwing the fingers 17 of the bar 16, out of alinement with each other. These projections 17 extend through the spaces in the 5 periphery of the lantern pinion, and when the key is rotated the lantern pinion is also rotated, and owing to the interengagement of the lantern pinion, bars, and the rack teeth on the sliding bolt, the sliding bolt 10 will be retracted or advanced, as the case may be. It will be further noted that the rack teeth of the sliding bolt are further provided with a set of notches 31 which are adapted to receive the extremities 17 of the 15 member 16. Were these notches not provided, the lantern pinion could not be rotated because of the fact that the rack teeth could not enter the spaces in the lantern pinion at the points where the extremities 20 17 projected therethrough.

A by-pass 32 is formed between the rack teeth of the sliding bolt which is adapted to receive the disk 13 when said disk has been pushed in owing to the insertion of the key.

25 The lock may be actuated from the inside of the door without the use of a key by exerting a pull on the knob; this movement causes the tumbler to move to the left in Fig. 1, until the pin 22 is out of engagement 30 with the knob 21. The pin 22 then being disposed within the groove 20, the knob may be rotated and the bolt 14 will be consequently rotated.

The lock bolt is held in position by a 35 bridge 34 secured by means of screws 35.

Having now fully described my said invention, what I claim and desire to secure by Letters Patent, is:

1. In a lock of the kind described the 40 combination with the tubular lock body of a lock bolt, means for guiding the said lock bolt transversely with reference to the said tubular body, a toothed rack provided on the said lock-bolt, a spring controlled piston 45 slidably and rotatably engaged in the said tubular body, a pinion on the said piston, a key adapted to shift and rotate the said piston in the said tubular body, spring controlled small bars axially and slidably 50 mounted in said piston, arms formed at right angles at one end of said bars and adapted to form additional teeth of the said pinion and means provided on the key and adapted to shift the said small bars 55 independently of the said piston so as to cause the said arms to coincide with said toothed rack of the lock bolt, substantially as and for the purpose set forth.

2. The combination with a lock casing, 60 of a rotatable and slidable tumbler within the casing, a pinion formed on the tumbler and a sliding ward within the pinion and tumbler, a sliding bolt provided with rack teeth which are adapted to engage the

pinion, projections on the sliding ward 65 which project through the periphery of the pinion, and a plurality of notches formed in the rack teeth of the sliding bolt which are adapted to receive the extremities of the sliding ward when the tumbler is rotated. 70

3. The combination with a lock casing, of a slidable and rotatable tumbler located therein, said tumbler being provided with an annular groove and a lantern pinion, a longitudinal notch in the periphery of the 75 tumbler, a pin projecting within the casing adapted to engage the aforesaid notch, a sliding bolt provided with rack teeth for engagement with the lantern pinion, resilient means for urging the tumbler toward 80 one end of the casing for the purpose of holding the pin engaged within the notch, and means for permitting the insertion of a key whereby the tumbler may be slid until the pin is seated within the annular groove 85 and whereby the tumbler may be rotated for the purpose of retracting or advancing the sliding bolt.

4. The combination with a lock casing, of a rotatable and slidable tumbler located 90 therein, said tumbler being provided with a lantern pinion and a recess which is adapted to receive a sliding ward, said sliding ward being in the form of a rod which is longitudinally split to form two halves, 95 the ends of the halves being bent outwardly and away from each other, resilient means for urging the sliding ward toward one end of the tumbler for the purpose of seating the extremities thereof in a pair of notches 100 adapted to receive them and which are formed in the end of the lantern gear, said extremities being adapted to project between the teeth of the lantern pinion, a plurality of notches formed in the teeth of 105 the sliding bolt which are adapted to receive the extremities of the ward during the operative position of the lock, and means whereby a key may be inserted for the purpose of forcing the sliding ward and its 110 extremities into the path of movement of the rack teeth for the purpose of rotating the tumbler.

5. The combination with a lock casing, 115 of a rotatable and slidable tumbler, a lantern pinion mounted on the tumbler, a sliding bolt provided with rack teeth which are adapted to engage the lantern pinion, a sliding ward centrally located within the tumbler, said ward being formed of two 120 sliding bars having their ends bent outwardly and away from each other, said ends being further adapted to project between the teeth of the lantern pinion, one end of the lantern pinion being provided with notches 125 which are adapted to receive the ends of the ward in one position thereof, resilient means for urging the ward forward for retaining

the ends thereof within the notches, a key which is adapted to be inserted within the tumbler for the purpose of engaging the tumbler and to push the ward backward, 5 means on the key for throwing the ends of the ward out of alinement with each other, and means whereby the tumbler may be rotated to retract or advance the sliding bolt, and a plurality of notches formed in the

rack teeth of the sliding bolt to receive the 10 ends of the ward.

In testimony whereof I have hereunto set my hand in presence of two witnesses.

ALFRED LECLERC.
